1 Claim. (Cl. 222—55)

ABSTRACT OF THE DISCLOSURE

A pair of electro-magnetically driven vibratory feeders are arranged in series, feeding from a hopper to a weigh pan. A capacitive depth control sensitive to the depth of material on the second conveyor is arranged of material on the second conveyor is arranged to control the amplitude of vibration of the first conveyor.

This invention relates to material feeding apparatus and has as an object to provide such apparatus in a convenient form.

Material feeding apparatus in accordance with the invention comprises a first conveyor, first drive means for driving said first conveyor to advance material along said first conveyor, a second conveyor arranged to receive material delivered by said first conveyor, second drive means for driving said second conveyor to advance material along said second conveyor, means sensitive to the depth of material on the second conveyor and control means operable by said depth sensitive means for controlling said first drive means to vary the rate of delivery of material by the first conveyor so as to tend to keep the depth of material on the second conveyor constant.

Reference is now made to the accompanying drawings in which:

FIGURE 1 is a diagrammatic view illustrating an example of the invention,

FIGURE 2 is an elevation of an embodiment of the invention, and

FIGURE 3 is an electrical circuit diagram showing the full electrical arrangement used in the example of the invention described.

Referring to the drawings, material feeding apparatus is required to feed material from a hopper 10 to a weighing apparatus 11. The weighing apparatus 11 is provided with any convenient means 12 which may be in the form of a switch, for arresting feed of material after a predetermined weight has been fed.

In the example described, the feeding apparatus is of the vibratory type, and in fact consists of two vibratory trays 13, 14, the first 13, of which receives material from the hopper 10 and delivers it to the second tray 14 which in turn delivers the material to the weighing mechanism 11.

A tray 13 is supported on a first body 15 through the intermediary of a pivoted link 16, and a leaf spring 17. The arrangement of the leaf spring 17 is such that when the tray is in repose, as shown, the leaf spring 17 and the link 16 extend in parallel directions inclined to the tray 13. Thus reciprocatory movement of the tray 13 will be accompanied by rising and falling of the tray. As the tray is advanced it rises and as the tray retreats in the direction opposite that in which it is desired to feed the material, the tray falls. Secured to the tray is a further magnetic armature 18 which co-acts with a coil 19 to drive the tray. The body 15 is carried on springs 20 on a base 21.

2

The tray 14 is supported in an essentially similar manner on a body 22 carried by springs 23 on the base 21. An armature 24 is secured to the underside of the tray 14, and co-acts with a coil 25. The tray 14 is at a lower level than the tray 13, and the two trays overlap so that material falling from the tray 13 is caught by the tray 14.

The coil 25 is supplied with power from an A.C. source 26 through the intermediary of a series circuit consisting of the switch 12, a variable resistor 27 and a diode 28. Whenever the switch 12 is closed, therefore, current will flow through the coil 25 during alternate half cycles of the supply, the magnitude of the current being dependent upon the setting of the variable resistor 27. When the switch 12 is opened by the weighing mechanism, the tray 14 will come to rest.

In order to ensure that the material which falls from the tray 14 after the switch 12 has been opened is kept constant, it is desirable to ensure that the depth of material on the tray 14 is also kept constant. This is effected by controlling the amplitude of the vibrations of the first tray 13 in accordance with the measured depth of material on the second tray 14. To this end there is provided means sensitive to the depth of material on said second tray. Such means consists of a capacitive probe plate 29 supported over the tray 14, which is earthed. The combination of the probe 29 and the earthed tray 14 are represented in FIGURE 3 by the variable capacitor 30.

As shown in FIGURE 2, the probe plate 29 is adjustably mounted over the tray 14, so that adjustment of the depth of material on the tray 14 can be effected by varying the height of the probe plate 29. The probe plate is suspended by a rod 31 from a unit 32 which includes the circuit elements immediately associated with the probe plate 29. The unit 32 is in turn supported on a stand 33 on the base 21, the upper end of the strand 33 is constituted by a vertical screw 34 on which a bracket 35 is mounted by means of upper and lower adjusting screws 36, 37, a rod 38 secured to the unit 32 is screw-threaded and is similarly adjustable relative to the bracket 35 by means of nuts 39, 40.

Turning now to FIGURE 3, it will be seen that the power supply for the unit 32 is derived from the A.C. source 26 through the intermediary of a transformer 41. The secondary winding of this transformer has a centre tapping which is earthed. The respective ends of the secondary winding are interconnected by a capacitor 42 and are connected respectively to the anodes of a pair of diodes 43, 44, the cathodes of these two diodes are connected together and are earthed through a capacitor 45. In addition, the cathodes are connected through a resistor 46 and a pair of Zener diodes 47, 48 in series to earth, the anode of the Zener diode 48 being connected to earth, and the cathode of the Zener diode 47 being connected to the resistor 46. In effect therefore, the potential of the cathode of the diode 47 remains at a substantially constant level at all times. The input terminal 49 of the unit 32 is connected to the cathode of diode 47.

The unit 32 includes a high frequency oscillator including an n-p-n transistor 50. The base of this transistor is connected to one end of one of a pair of primary windings 51, 52 of a transformer 53, the other end of primary winding 51 is connected through a resistor 54 to earth, the resistor 54 being bridged by a capacitor 55. The collector of transistor 50 is connected to one end of the other primary winding 52, the other end of which is connected through a resistor 56 to the terminal 49. The emitter of transistor 50 is connected to earth through a resistor 57. The said other ends of the primary windings 51, 52 are interconnected by a resistor 58, and the series

circuit constituted by the resistors 54, 58 is bridged by a capacitor 59.

The output of the high frequency oscillator is taken from the secondary winding 60 of the transformer 53. This winding is bridged by a pair of capacitors 61, 62 in series, with their interconnections earthed. Thus the secondary winding 60 provides at its ends two output voltages which are equal in amplitude but of opposite phase relative to earth. The variable capacitors 30 (which is in fact constituted by the probe plate 29 and the tray 14) has one plate connected to earth and the other plate connected to one end of the winding 60 through the intermediary of a capacitance 63 and a variable capacitance 64 in series. The capacitors 30 thus forms one arm of a capacitive potential divider, the other arm of which is constituted by the capacitors 63, 64 in series. The amplitude of the signal at the connection 65 (which is connected to the probe plate 29) will therefore vary in accordance with the capacitance for the time being of the capacitors 30. The interconnection 65 is connected to the input terminal 66 of an A.C. amplifier through a capacitor 67 of very low capacitance. In order to prevent high standing voltages from being applied to the input terminal 66, this is connected through a capacitor 68 and a variable capacitor 69 in series to the other end of the winding 60 so as to apply a signal of opposite phase to the terminal 66. By suitable adjustment of the capacitor 69 it can therefore be arranged that the changes in the amplitude of the signal at terminal 66 are not small compared with the standing voltage there.

The terminal 66 is connected to the base of an n-p-n transistor 70 which is also connected through a resistor 71 to the terminal 49, and through a resistor 72 to earth. A resistor 73 connects the emitter of transistor 70 to earth. The collector of transistor 70 is connected through a parallel tuned circuit to the terminal 49, the tuned circuit consisting of the primary winding of a variable transformer 74, and a capacitor 75.

The secondary winding of the transformer 74 has one end earthed, and the other end connected to the anode of a diode 76, the cathode of which is connected to one end of a potentiometer 77 earthed at the other end. The potentiometer is bridged by a capacitor 78. The variable point of the potentiometer is connected to the input terminal 79 of a control circuit for controlling the current to the coil 19.

The control circuit is operated by a pulsed D.C. supply derived from the transformer 41. It will be seen that the anode of the diode 44 is connected to the anode of a diode 80, the cathode of which is connected through a resistor 81 to the cathode of a Zener diode 82. The anode of the Zener diode 82 is earthed. At the cathode of the Zener diode 82 therefore, D.C. pulses in synchronism with alternate half cycles of the A.C. supply. A potential divider consisting of resistors 83, 84 is connected across the Zener diode 82 and the interconnection of the resistors 83, 84 is connected to one end of the primary winding 85 of a transformer 86, the other end of this winding 85 is connected to the base of an n-p-n transistor 87. The collector of transistor 87 is connected to one end of one of the secondary windings 88 of the transformer 86, the other end of winding 88 being connected to the cathode of the Zener diode 82. The collector of transistor 87 is also connected to the above of a diode 89 having its cathode connected to the cathode of Zener diode 82. The resistors 83, 84, the transformer 86, the transistor 87 and the diode 89 form a blocking oscillator which oscillates when a signal is applied to the emitter of transistor 87.

This signal is applied by means of an n-p-n transistor 90 with its emitter connected via a resistance 91 to earth, and its collector connected through a capacitor 92 to the cathode of the Zener diode 82 and to the emitter of transistor 87. Thus, in use, the blocking oscillator will oscillate during alternate half cycles of the supply commencing a variable time after the commencement of the

appropriate half cycles. The time delay depends upon the D.C. signal applied to the base of the transistor 90. When a transistor 90 is hard-on the capacitor 92 will be charged rapidly and oscillation will commence early. When, on the other hand, the transistor 90 has only a small signal applied to its base, there will be a comparatively long delay before oscillation commences.

The D.C. signal at terminal 79 of the probe unit 32 is amplified and applied to the base of transistor 90. The amplifier consists of two transistors 93, 94 having their emitters connected to earth through a common resistance 95. The base of transistor 94 is connected to terminal 79, and its collector is connected to the cathode of the Zener diode 82 through a resistor 96. The collector of transistor 93 is connected to the cathode of Zener diode 82 by a resistor 97, and directly to the base of transistor 90. The base of transistor 93 is held at a substantially steady potential derived from a potential divider 98, across the resistor 46. The mid-point of this divider is connected to the base of transistor 93 through a resistor 99 and the base of resistor 93 also receives a bias from resistors 100, 101 in parallel and connected to earth.

The coil 19 for driving the first tray 13 is connected across the A.C. source in series with a silicon controlled rectifier 102. The gate-cathode circuit of this silicon controlled rectifier consists of a winding 103 of the transformer 86, and a resistor 104 in series. A capacitor 105 interconnects the anode and cathode of the rectifier 102.

It will be appreciated that the capacitance of the probe capacitor 30 will vary in accordance with the depth of material on the tray 14. Its capacitance will be at a minimum when the tray is empty, and will rise irrespective of whether the material on the tray is conductive or dielectric, the dielectric constant for most solids being considerably in excess of unity. Thus, the amplitude of the A.C. signal at terminal 66 decreases as the level of material on the tray 14 increases. Thus the D.C. signal applied to the output terminal 79 of the probe device decreases as the level rises. As the signal at terminal 79 decreases, the current flowing through resistor 95 decreases, thereby creating a smaller voltage drop across the resistor 95. The transistor 93 is thereby rendered more conductive, and a considerable drop in the potential at the base of the resistor 90 is therefore experienced. This in turn increases the delay at the start of each alternate half cycle of the A.C. supply before the blocking oscillator commences its oscillations, and causes firing of the silicon controlled rectifier 102. Thus, as the level of material on the tray increases the power delivered to the coil 19 decreases and thus the amplitude of the vibration of the tray 30 is likewise decreased. A stable equilibrium condition exists in which changes in depth of the material on the tray 14 are rapidly connected by variation of the amplitude of vibration of the tray 30. The rate at which material is fed for a given material and arrangement of the probe 29 is determined solely by the variable resistor 27 in the circuit of the coil 25. As the amplitude of vibration of the tray 14 is varied, by adjustment of resistor 27, the amplitude of vibration of the tray 13 will be automatically varied to keep the depth of material on the tray 14 constant. The depth of material can, however, be varied by adjusting the height of the probe plate 29, or, alternatively, adjusting capacitor 64 or 69.

Having thus described my invention what I claim as new and desire to secure by Letters Patent is:

1. Material feeding apparatus comprising a first conveyor and first drive means therefor, said first conveyor comprising an elongated tray mounted for reciprocatory movement and said first drive means comprising an electro-magnet having a coil and an armature mounted respectively on said tray and a base on which said tray is supported, a second conveyor arranged to receive material from said first conveyor and second drive means for driving said second conveyor to advance material along such second conveyor, a capacitive probe plate supported

over said second conveyor and connected in an A.C. control circuit for said electro-magnet, said A.C. control circuit comprising a semiconductor controlled rectifier having an anode-cathode circuit in series with said coil and also having a gate to which pulses are delivered by said A.C. control circuit to initiate conduction of said semiconductor controlled rectifier, said capacitive probe plate and the second conveyor forming, in combination, a capacitor which is part of an A.C. potential divider, said A.C. control circuit delivering a conduction initiating pulse to said gate at an instant after the commencement of each conductive half cycle of said semiconductor controlled rectifier determined by the magnitude of an A.C. signal generated by said A.C. potential divider dependent on the depth of material on said second conveyor, where-
by the rate of delivery of material to the second conveyor

by the first conveyor is varied to keep a depth of material on the second conveyor constant.
